DESK PAD CLIP

Albert F. Rippel, Greenwich, Conn.

Application September 11, 1935, Serial No. 40,158

3 Claims. (Cl. 120—24)

My invention relates to a desk pad clip, and it consists in the constructions, arrangements and combinations herein described and claimed.

It is a purpose of my invention to provide a clip which may be readily associated with a desk pad for holding the pad against shifting movement relative to the forward edge of a desk top, thereby maintaining the pad in orderly fashion upon the desk.

10 It is also an object of the invention to provide a clip which may be stamped and formed in a single machine operation, permitting the clip to be sold at an extremely low cost.

Additional objects, advantages and features of 15 invention will be apparent from the following description considered in conjunction with the accompanying drawing, wherein

Figure 1 is a perspective view illustrating my clip in use.

20 Figure 2 is a cross section on the line 2—2 of Figure 1.

Figure 3 is a top plan view of the clip.

Figure 4 is a perspective view thereof.

Referring to Figures 1 and 2, I have shown 25 generally, a desk top 10 upon which a pad 11 is supported, the pad being of the well known construction in which the blotter 12 is confined to the pad by corner pockets 13. These pockets 13 have their open edges disposed toward the 30 medial portion of the pad, and when in use, two of the pockets will be positioned so as to lie flush with the forward edge of the desk, as may be seen in Figure 1, and it is in such position that it is desired that the pad should be maintained, and 35 which I accomplish by use of a pair of clip members 14.

The clip members 14 are identical in construction, and therefore a description of one will be sufficient for full understanding thereof. Attention 40 is particularly invited to Figures 3 and 4 wherein the clip is shown as formed from a rectangular blank of sheet material, such as aluminum, although any material having the necessary rigidity may be employed. The blank comprises a head 15, of a length less than one-half of the length of the blank, the blank being longitudinally slotted as at 16, thereby defining a pair

of leg members 17. The head 15 is bent through its medial portion as indicated at 18, the bend occurring in a line coincident with the slot 16. Thus, the leg members 17 will be disposed at right angles to each other, as may be clearly seen in Figure 4.

In use, the desk pad 11 is positioned upon the desk so that one edge thereof lies flush with the edge of the desk which will, of course, position a pair of pockets 13 adjacent the edge of the 10 desk. One of the clips 14 is employed in conjunction with each pocket, and is applied therein by inserting one of the legs 17 in the pocket, which will be permitted by the slot 16, the other leg resting flush upon the flat edge of the desk top. 15 With a clip so engaged with each pocket, it will be apparent that the pad 11 will be retained against movement away from the edge of the desk and will be maintained in orderly fashion upon the desk top.

20 While I have shown and described a preferred construction, I am aware that changes in structure may be made, and I therefore consider as my own all such modifications as fairly fall within the scope of the appended claims.

25 I claim:

1. In combination, a pad having a pair of pockets positioned adjacent one edge thereof, a clip member for each pocket, said clip members having a pair of leg members arranged at right 30 angles to each other, one of said legs being disposed within respective pockets, and the other of said leg members being disposed flush against an edge of a desk.

2. A desk pad clip comprising a body member 35 having a pair of leg members, one of said leg members being adapted to engage a pad to be retained upon a desk top, and the other of said leg members engaging an edge of a desk.

3. A desk pad clip comprising a body member 40 having a slot longitudinally thereof defining a pair of leg members, said body member being bent in a plane coincident with the slot whereby to position said leg members at right angles to each other.

45 ALBERT F. RIPPEL.
